UNITED STATES PATENT OFFICE

FRANK THOMPSON, OF CAMDEN, NEW JERSEY, ASSIGNOR TO C. HOWARD HUNT PEN COMPANY, OF CAMDEN, NEW JERSEY, A CORPORATION OF NEW JERSEY

PENCIL SHARPENER

Application filed May 3, 1929. Serial No. 360,142.

My invention relates to an improvement in pencil sharpeners and more particularly to the provision of means for insuring unintentional removal of the chip receptacle.

5 As is well known, pencil sharpeners comprise a support adapted to be secured to a wall, table, or the like, and from which is supported a sharpening device, a chip receptacle, removably attached to the support, 10 being provided to collect the chips resulting from the sharpening operation. In pencil sharpeners as heretofore constructed the chip receptacle has been attached to the support through the medium of a bayonet joint which 15 acts to desirably position the chip receptacle, but which has no capacity for retaining the receptacle if it be accidentally moved in a direction to release the joint.

In the case of pencil sharpeners as heretofore constructed, the chip receptacles are frequently detached from the support and their contents spilled inadvertently, as by being brushed by a person passing, or otherwise.

25 Now it is the object of my invention to provide means for insuring against accidental detachment of the chip receptacle without at the same time rendering its detachment when desired any more difficult than in present structures.

In accordance with my invention, I provide, in addition to the usual form of connection between the chip receptacle and support, resilient means adapted to releasably 35 lock the receptacle to the support after it is attached thereto through the medium of the ordinary attaching means. In accordance with my invention I may, for example, provide a spring catch, which may be conveniently carried by the chip receptacle in such a position as to engage with the support when the chip receptacle is attached thereto in the usual manner. The resilient means in 40 accordance with my invention, as, for example, a spring catch, may be readily released, but when engaged will prevent turning of the chip receptacle in a direction to release the receptacle from the ordinary means by 45 which it is attached to the support, thus in-

suring against accidental release of the receptacle.

Having indicated in a general way the nature and purpose of my invention, I will proceed to a detailed description with reference to the accompanying drawings, in which there has been illustrated a preferred embodiment and in which:

Fig. 1 is a side elevation of a pencil sharpener embodying my invention.

Fig. 2 is a rear end elevation of the chip receptacle embodying my invention.

Fig. 3 is a sectional view on line 3-3 of Fig. 1.

Fig. 4 is a perspective view partly in section of an element of a bayonet joint for attaching the chip receptacle to the support.

In the drawings, A is a support provided with a base portion b and a head c. Within the head portion c of the support is the usual gear mounted on a shaft which bears in an extension c' from the head and is provided with a handle D. E indicates a cutter carrier, extending from the shaft carrying handle D and provided with a pencil guide f, which carries cutters G G provided with gears meshing with the gear in the head portion c, all as is usual in pencil sharpeners.

H is a chip receptacle of any desired construction, as, for example, having heads i between which is arranged a body j of transparent material. The rear head i of the chip receptacle is provided with an aperture about which is one element k of a bayonet joint adapted to cooperate with complementary elements l provided on a flange m, carried by the head portion c of the support. The forward head i of the chip receptacle is provided with an aperture for the insertion of a pencil to be sharpened and desirably with a gauge n for the support of various sizes of pencils. The gauge n, which, as is well known, is provided with a number of apertures of different sizes, is pivotally connected to the head i in order that, by its rotation, its various apertures may be respectively aligned with the pencil inserting aperture in the head.

On the rear head i of the chip receptacle is secured a spring catch o and where, as is usual,

the body of the support A is of curved section, a notch *p* is cut therein.

The operation of the device in accordance with my invention will be apparent from the above description taken with the drawings. The chip receptacle H is detachably secured to the support A in the usual manner; i. e. by engaging the bayonet joint with the body of the chip receptacle at an angle to its normal position and turning the receptacle to its normal position, thus fully closing the joint. When the bayonet joint is fully engaged, the chip receptacle can only be turned out of normal position in reverse direction to that in which it is turned to close the joint. The spring catch *o* is so arranged that when the receptacle reaches normal position the catch will engage within the body of the support, as clearly shown in Fig. 3. With the bayonet joint closed and the catch *o* engaged, as shown in Fig. 3, the chip receptacle cannot be moved in either direction and hence accidental release of the bayonet joint is positively prevented. When it is desired to detach the chip receptacle from the support, for example, for the purpose of emptying out the chips, such may be readily accomplished by releasing the spring catch *o*, which permits the receptacle to be turned in a direction to release the bayonet joint.

It will now be observed that by virtue of my invention the accidental detachment of chip receptacles is positively eliminated and, at the same time, when detachment is desired, such may be readily accomplished.

It will be appreciated that I do not intend that my invention shall be limited to the particular structure disclosed herein by way of illustration, since it will be obvious that the purposes of my invention may be accomplished by a variety of embodiments differing variously from that shown.

What I claim and desire to protect by Letters Patent is:

45 1. In a pencil sharpener, in combination, a support, a chip receptacle, means on the chip receptacle and support engaged by relative rotary movement of the receptacle and support to hold the former on the latter, and releasable cooperating means on the receptacle and support operative to prevent a reverse rotary movement tending to disengage the first mentioned means.

50 2. In a pencil sharpener, in combination, a support, a chip receptacle, means on the chip receptacle and support engaged by relative rotary movement of the receptacle and support to hold the former on the latter, and releasable spring detent means operative to prevent a reverse rotary movement tending to disengage the first mentioned means.

55 3. In a pencil sharpener, in combination, a support, a chip receptacle, bayonet joint connecting means on the chip receptacle and support engaged by relative rotary move-

ment of the receptacle and support to hold the former on the latter, and releasable cooperating means on the receptacle and support operative to prevent a reverse rotary movement tending to disengage the first mentioned means.

4. In a pencil sharpener, in combination, a support, a chip receptacle, bayonet joint connecting means on the chip receptacle and support engaged by relative rotary movement of the receptacle and support to hold the former on the latter, and releasable spring detent means operative to prevent a reverse rotary movement tending to disengage the first mentioned means.

In testimony of which invention, I have hereunto set my hand, at Camden, New Jersey, on this 29th day of April, 1929.

FRANK THOMPSON.
